UNITED STATES PATENT OFFICE.

FRED BIFFAR, JR., OF CHICAGO, ILLINOIS.

DESIGN FOR A POLICE-BILLY.

58,214.

Specification for Design.

Patented June 28, 1921.

Application filed September 27, 1919. Serial No. 328,076. Term of patent 14 years.

To all whom it may concern:

Be it known that I, FRED BIFFAR, Jr., a citizen of the United States, residing at Chicago, in the county of Cook and State of Illinois, have invented a new, original, and ornamental Design for a Police-Billy, of which the following is a specification, reference being had to the accompanying drawing, forming a part thereof.

I claim:—

The ornamental design for a police billy as shown.

FRED BIFFAR, JR.
